(57) **CLAIM**

The ornamental design for a LED light assembly, as shown and described.

DESCRIPTION

FIG. 1 is a top and side perspective view of an LED light assembly showing my new design, with the broken lines showing for illustrative purposes only and forming no part of the claimed design;

FIG. 2 is a top end view thereof;

FIG. 3 is a bottom end view thereof;

FIG. 4 is a first side view thereof;

FIG. 5 is a second side view thereof; and,

FIG. 6 is a third side view thereof opposite the second side view.

1 Claim, 6 Drawing Sheets
